Primary Examiner — Kevin K Rudzinski*Assistant Examiner* — Amber J Rabie(74) *Attorney, Agent, or Firm* — Banner & Witcoff, Ltd.(57) **CLAIM**

The ornamental design for a utility wrap, as shown and described.

DESCRIPTION

FIG. 1 is a top, front perspective view of a utility wrap showing our new design;

FIG. 2 is a bottom, front, left perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines depicting the remainder of the utility wrap show features that form no part of the claimed design.
